Claims priority, application Great Britain Nov. 9, 1956

4 Claims. (Cl. 317—31)

This invention relates to safety systems for nuclear reactors. When certain faults occur in a nuclear reactor it is necessary to effect an emergency shut-down. The shutting down action may be initiated by a relay which is normally energised from a reliable source through one or more contacts which are closed during normal operation. On the occurrence of a critical fault however, one or more of the contacts is opened to de-energise the relay, which thereupon initiates shut-down, substantially instantaneous operation of the relay on de-energisation thereof being required in order that the shut-down will be effected in a minimum of time.

The contacts referred to are commonly provided on control relays connected in a circuit which is energised from an A.C. source, and since faults developing in the supply system do not justify shutting down the reactor, a duplicate A.C. source may be provided as a standby which is automatically substituted for the other source in the event, say, of the voltage or frequency departing from a nominal value by more than a predetermined amount. The change-over from one source to the other necessarily occupies a period of time which usually will be longer than the permissible release time of the control relays, this release time being determined by the usually very small safe period for a critical fault. Thus in the event of a supply fault the control relays would become de-energised and bring about shutting down of the reactor. As previously stated this is undesirable and the purpose of the present invention is to provide a safety system which discriminates between critical reactor faults and a fault in the supply system so as not to shut down on the occurrence of such supply fault.

In the following disclosure of the invention reference to a relay as being normally energised relates to the condition of the relay during normal operation of the reactor, whereas reference to relay contacts as being normally open or closed relates to the condition of the contacts in the de-energised condition of their relay, whether or not this is the condition of the relay for normal operation of the reactor.

According to the present invention a safety system for a nuclear reactor comprises what will for convenience be termed a shut-down relay having an energising winding arranged to be normally energised from a first source of supply and on de-energisation to initiate shut-down of the reactor, at least one control relay arranged to be normally energised from one of two interchangeable further sources of supply and to be de-energised on the occurrence of abnormal operating conditions necessitating shut-down, said control relay having normally open contacts connected in series with the energising winding of the shut-down relay, and a pair of normally energised relays arranged for de-energisation in consequence of abnormal conditions in the energising supply for the control relay and respectively having normally open and normally closed contacts connected in series in a circuit which shunts the control relay contacts connected in series with said shut-down relay winding, that one of said

2

pair of relays whose said contacts are normally open having a delayed release time at least as great as the time taken to change over said sources supplying the control relay whereby during such changeover to maintain energisation of the shut-down relay through said shunt circuit irrespective of de-energisation of the control relay.

In order that the invention may be more fully understood, a particular embodiment thereof will now be described in conjunction with the accompanying drawing the single figure of which shows a circuit arrangement incorporating the invention.

Referring to the drawing, the reference CC designates an energising and control circuit for a shut-down relay SH of a nuclear reactor, which relay in known manner (not shown) controls the supply to the control rods of the reactor and is effective on its de-energisation to initiate a shut-down action. The circuit CC comprises in series with an energising winding *sh* and normally open contacts SH1 of the relay SH, normally open contacts SA1, SB1, SC1, and so on (the possible presence of other such contacts being indicated at 1) of a number of control relays SA, SB, SC . . . which are responsive to the occurrence of critical faults in respective sections FA, FB, FC . . . of the reactor. These control relays have their energising windings *sa*, *sb*, *sc* . . . connected in series with respective reactor section guard circuits (indicated at *fa*, *fb*, *fc* . . .) across an alternating current supply *ac* for energisation thereby during normal operation of the reactor, so that their contacts SA1, SB1, SC1 . . . establish an energising circuit for the relay SH across a reliable direct current source *dc*. On occurrence of a fault in the reactor, the guard circuit in the relevant section is broken to de-energise the winding of the corresponding control relay, which thereupon releases to open its contact in the control circuit CC and thereby de-energise the relay SH which on release initiates a shutting down action for the reactor. Since this action has to be effected as quickly as possible the control relays are so designed that their release lag is small. The contact SH1 is included in the energising circuit for its relay to prevent re-operation thereof irrespective of subsequent closure of the opened control relay contacts. To re-establish the energising circuit for the relay SH, a temporary shunt connection 2 is established in any suitable manner across contact SH1 until such time as this contact closes on operation of its relay. Connected in a shunt circuit across the control relay contacts SA1, SB1, SC1 . . . is a normally open relay contact UVT2 in series with a normally closed relay contact UV1: the purpose of these contacts, which are on a supply fault relay UV and a delayed release relay UVT respectively, will be dealt with presently when the operation of these relays is being considered.

As aforesaid, the control relays SA, SB, SC . . . are connected for energisation by the supply *ac*. This supply is fed from a power distribution board DB which is supplied from one of two alternating current supply sources AC1 and AC2, constituted for instance by respective motor driven alternators (not shown), one of which is selected as the normal supply source and the other as a standby source; the output from each source is made available at all times, that is, in the case of alternators they are both continuously running. On occurrence of abnormal conditions in the supply *ac* for the control relays, for instance, when an under-voltage or over-voltage or a departure from a nominal frequency occurs, a change-over circuit effects connection of the standby supply source to the power distribution board DB in substitution for the other supply source.

This change-over circuit comprises in respect of each supply source AC1 and AC2 a series circuit (C1 or C2)

connected across two phases of the appertaining source (assuming the supply sources to be three-phase as shown). For the supply source AC1 the series circuit C1 follows the path: phase line *r*, full-wave bridge rectifier arrangement *Rfa* feeding the energising coil *coa* of a relay COA which when operated connects the supply source AC1 through its normally open contacts COA2, COA3, and COA4 to the power distribution board DB; normally closed contact COB1 of a corresponding relay COB included in the series circuit for the supply source AC2; normally closed contact COH1 of a delayed release change-over relay COH; normally open contact UV5 of the supply fault relay UV; and phase line *y* of the supply source AC1. Connected in parallel with the contact UV5 is a normally open contact COH2 of the relay COH. For the supply source AC2 a similar series circuit C2 is provided over the path: phase line *r'*; full-wave bridge rectifier arrangement *Rfb* feeding the energising coil *coa* of the relay COB, which relay when operated connects the supply source AC2 through its normally open contacts COB2, COB3 and COB4 to the power distribution board DB; normally closed contact COA1 of the relay COA; normally closed contact COH3 of the relay COH, normally open contact UV4 of the relay UV, and phase line *y'*. Connected in parallel with the contact UV4 is a normally open contact COH4 of the relay COH.

The supply fault relay UV has its energising coil *uv* connected across the supply *ac* in series with a normally open contact UV3 of the relay UV, normally open contact FR1 of a frequency-sensitive relay FR, and normally open contact HV1 of a high voltage relay HV. The relays FR and HV, which have their respective energising windings *fr* and *hv* connected directly across the supply *ac* for operation thereby during normal supply conditions, are respectively arranged to release, when the supply *ac* departs from a nominal frequency and when it exceeds a predetermined voltage, thereby breaking at their respective contacts FR1 and HV1 the energising circuit for the relay UV; this latter relay itself is normally releasable on the supply *ac* falling below a predetermined value.

For selecting one of the supply sources AC1 and AC2 to supply the power distribution board DB, there is provided a two-position selection switch S having contacts S1 associated with the series circuit C1 for the supply source AC1, and contact S2 associated with the series circuit C2 for the supply source AC2. With the contacts of the switch S in position 1 the circuit is so arranged that when the supply sources AC1 and AC2 are initially switched on (it being appreciated that there is no supply *ac* at this time and that therefore none of the relays connected across this supply are energised), the relay COB is energised from the supply source AC2 over the series circuit C2, open contact UV4 being shunted by the switch contact S2. Consequently the supply AC2 is connected through contacts COB2, COB3, and COB4 of relay COB to the power distribution board DB. If the contacts of the switch S had been in position 2 the relay COA would have been energised from the supply source AC1 over the series circuit C1 (contact UV5 being shunted by virtue of the position of switch contact S1 in this instance) to connect this supply through contacts COA2, COA3, and COA4 to the power distribution board DB.

Following connection of one of the supplies AC1 or AC2 to the distribution board DB in the manner just described, the change-over relay COH is operated as by depressing a push button H to connect its energising winding *coh* across a source V. Assume firstly that the supply sources AC1 and AC2 have been switched on with the selection switch S in position 1 so that relay COB has been operated and at its contacts COB2, COB3, and COB4 has connected the supply source AC2 to the power distribution board DB. Under these conditions, the supply *ac* is available at the power distribution board DB and therefore the relay circuits connected across this supply are energised. Relay UV is therefore operated at this time

and contacts UV4 and UV5 are closed, contact UV4 providing a hold circuit for relay COB independently of contact S2 of the switch S, while contact UV5 prepares an energising circuit for relay COA, this latter circuit being incomplete however because contact COB1 is open. When change-over relay COH is operated with the circuit in this condition, contact COH3 opens to break the energising circuit for relay COB and contact COH2 completes the energising circuit for relay COA once relay COB is released and its contact COB1 is restored to its normally closed position: contacts COH1 and COH4 are ineffective for this switch position. The inherent delay in the change-over operation, even although the output from the supply source AC1 is immediately available through contacts COA2, COA3, and COA4 to the power distribution board DB, causes a momentary interruption in the supply *ac* with the result that relay UV will release temporarily during the change-over operation. However, while relay COH is operated, the energising circuit for relay COA is independent of contact UV5 since the latter is shunted by contact COH2. The release time of relay COH is therefore made long enough to bridge the period while UV is released. Once the relay UV has re-operated the change-over relay COH can be released. The energising circuit for relay COA is then dependent on relay UV remaining operated, and the energising circuit for relay COB is held open at COA1. In this way the source AC1 is established as the normal source providing the supply *ac*, while the source AC2 constitutes the standby source.

If the selection switch S had been in position 2, so that the source AC1 was initially connected to the distribution board DB, operation of the relay COH would have changed over the sources AC1 and AC2 in a similar manner to that just described: that is, contact COH1 would have broken the initially established energising circuit for relay COA, while contact COH4 established an energising circuit for relay COB. Once the change-over relay COH had been released, the relay COB would remain energised over contacts COA1, COH3, and UV4, with the energising circuit for relay COA held open at contact COB1. Thus the source AC2 would have been established as the normal source and AC1 as standby.

The fault relay UV cannot operate unless the supply *ac* has been established by the connection to the distribution board DB of one of the sources AC1 or AC2, that is, unless one of the relays COA or COB has been operated. As will appear however, it is required that, whichever source AC1 or AC2 is selected as the normal source, continued energisation of the relay COA or COB associated with that source should be dependent on the fault relay UV being operated. Consequently the de-energised condition of relay UV existing prior to the establishment of the supply *ac*, prevents operation of whichever of the relays COA or COB pertains to the selected normal source AC1 or AC2 and thus prevents the supply *ac* from initially being obtained from that source. It is for this reason that the standby source is initially and temporarily connected to the distribution board DB. Moreover, the arrangement provides a convenient test that the standby source is initially without fault, since if such fault existed the relay UV would fail to operate.

If, after the establishment of one of the sources AC1 or AC2 as the normal source, some abnormal condition arises in the supply *ac*, the fault relay UV will release to interrupt the energising circuit for the then energised relay COA or COB at contact UV5 or UV4 respectively. Consequent upon this, contact COA1 or COB1 of the released relay COA or COB, completes the energising circuit for the other of these relays so that the standby supply source is connected through the contacts thereof to the distribution board DB. It will be seen that in either case the energising circuit just mentioned follows a path which shunts the appertaining (UV4 or UV5)

contact of the fault relay UV by way of the appertaining contact (S2 or S1) of the selection switch S.

The interruption caused in the supply *ac* on a change-over of the supply sources results in de-energisation of the control relays SA, SB, SC . . . which, in view of their necessarily short release time as previously explained, break the energising circuit established through their contacts SA1, SB1, SC1 . . . for the shut-down relay SH. To prevent the reactor being shut down unnecessarily in these circumstances, an alternative energising circuit for the shut-down relay SH is temporarily established during the change-over period. To this end, the contacts SA1, SB1, SC1 . . . of the control relays are shunted by the circuit consisting of the normally closed contact UV1 of the fault relay UV in series with the normally open contact UVT2 of the delayed release relay UVT. The energising winding *uv1* of relay UVT is fed from a bridge rectifier arrangement *Rfc* which is connected across the supply *ac* in series with a normally open contact UV2 of the fault relay UV, the relay UVT thus being de-energised, although not immediately released (by virtue of its release lag), on release of the fault relay UV. In the energising circuit for the relay UV a normally closed contact UVT1 of the delayed release relay UVT, is connected in parallel with the normally open contact UV3 to provide a circuit for initially energising the fault relay UV independently of this latter contact. Following energisation of relay UV its contact UV3 shunts the contact UVT1 so that the energisation is not interrupted by the subsequent opening of contact UVT1 on operation of relay UVT. Should fault relay UV be released, for any of the reasons previously mentioned, it cannot be re-operated until its energising circuit is re-established at contact UVT1 after the delayed release relay UVT has timed out.

Under normal operating conditions the shunt circuit across the control relay contacts SA1, SB1, SC1 . . . is open at contact UV1 of the then energised fault relay UV, the delayed release relay contact UVT2 in series therewith being closed. On occurrence of an abnormal condition in the supply *ac* both these relays become de-energised and the relay UV, in addition to changing over the supply source in the manner previously described, closes its contact UV1 in the shunt circuit across the control relay contacts SA1, SB1, SC1 . . . Since the contact UVT2 of the relay UVT does not immediately open an alternative energising circuit is temporarily established for the shut-down relay SH through contacts UV1 and UVT2, preventing its de-energisation even although the control relays SA, SB, SC . . . may release as a result of the interruption of the supply *ac*. This condition continues until the relay UVT has timed out by which time the change-over of the supply sources should have been successfully completed. On releasing, relay UVT closes its contact UVT1 to permit re-energisation of relay UV and opens its contact UVT2 to render the control relays SA, SB, SC . . . again effective to control the energisation of the shut-down relay SH. Energisation of relay UV if the standby source is in order then closes contacts UV2 to re-energise relay UVT.

In providing a circuit arrangement incorporating the invention some of the relays and their contacts may be duplicated to ensure safety in case of failure thereof. Moreover spare circuits identical with those described may be provided so that maintenance thereon may be effected without having to shut down the reactor.

What I claim is:

1. A safety system for a nuclear reactor or the like comprising: a shut-down relay having an energizing winding arranged to be normally energized from a first source of supply and on de-energization to initiate shutdown of the reactor; at least one control relay arranged to be normally energized from one of two interchangeable further sources of supply and to be de-energized on the occurrence of abnormal operating conditions necessitating shut-down, said control relay having a normally open contact connected in series with said energizing winding of said shut-down relay; and a pair of normally energized relays arranged for de-energization in consequence of abnormal conditions in the energizing supply for the control relay and respectively having a normally open contact and a normally closed contact connected in series in a circuit which shunts said control relay contact connected in series with said shut-down relay winding, that one of said pair of relays whose said contact is normally open having a delayed release time at least as great as the time taken to change over said sources supplying the control relay whereby during such change-over to maintain energization of the shut-down relay through said shunt circuit irrespective of de-energization of the control relay.
2. A safety system as claimed in claim 1 wherein said pair of relays comprises a fault relay connected to be normally energized from the same supply as said control relay and to be de-energized in consequence of abnormal conditions therein, and a delayed release relay connected for energization from this same supply through a normally open contact of the fault relay, the fault relay having a normally closed contact in said shunt circuit and the delayed release relay having a normally open contact therein.
3. A safety system as claimed in claim 2 wherein said fault relay possesses a normally open contact connected in its own energizing circuit and the delayed release relay has a normally closed contact shunting said normally open contact of the fault relay.
4. A safety system as claimed in claim 1, wherein there is provided for said interchangeable sources of supply a change-over circuit comprising in respect of each of these sources a series connection energizable from the appertaining source and including: the energizing winding of a connection relay effective when energized to establish connection of that source as the control relay supply; a normally closed contact of the connection relay in the corresponding series connection pertaining to the other source; a normally closed contact of change-over switching means; and a parallel connection comprising a normally open contact of said switching means and a normally open contact of one of said relays de-energizable by abnormal control relay supply conditions, which series connections have connected therewith selection switching means having a first position in which the normally closed change-over contact in one of the series connections and the contacts in said parallel connection in the other series connection are rendered ineffectual, and a second position in which the corresponding contacts in the alternate series connections are rendered ineffectual.
